FLOOR BLOCK

Clarence C. Fulbright, Pine Bluff, Ark.

Application February 19, 1935, Serial No. 7,259

7 Claims. (Cl. 20—8)

The invention relates to floor blocks of the sort which are fabricated of slats assembled at the mill ready for assembly with other blocks at the job to form a floor.

5 For many years it has been known to assemble floor blocks at the mill, British patent to Seiler No. 684 of 1854 showing such practice, utilizing iron or wooden splines inserted into grooves in the back of the block.

10 In all such blocks of which I am aware, the splines have only the function of holding the blocks in assembly, and to resist warping purely by the hold of the spline. The resistance to warping of such blocks has depended entirely upon 15 the hold the splines have upon the material of the slats of which the blocks are composed, either by virtue of glue or dovetailing, in the case of wooden splines or dowels, or of some biting into the wood of the slats, in the case of metal splines. 20 Once such blocks are warped or separated by expansion and subsequent contraction, with consequent slippage of the hold, there has been little if any action on the part of the spline to again return the block to a plane surface or to draw the 25 slats back together.

It is an object of the present invention to provide a contractile spring acting to hold slats into assembly to form a flooring block.

It is a further object of the invention to provide 30 a contractile spring acting also as a spline to hold the slats into assembly in a block and to maintain them in a common plane.

It is a further object of the invention to provide 35 a block comprising slats held together by a contractile spring acting to hold the slats in a common plane and to draw the slats together when they become separated.

It is a further object of the invention to provide 40 a block formed of slats held together by a spline placed in their bottom, the spline having resiliency to allow flexure of the block and serving as a contractile spring to return the blocks to their original plane when moved therefrom.

45 Further objects of the invention will appear from the following description when read in connection with the accompanying drawing showing 45 illustrative embodiments of the invention, and wherein:—

50 Figure 1 is a bottom plan view of an assembled block;

Fig. 2 is a section on line 2—2 of Fig. 1;

Fig. 3 is a like section showing a different form varying in details from that of Figs. 1 and 2; and

55 Figs. 4 and 5 are plan views respectively of

forms of spring which may be used in the invention.

As shown, the finished block is formed of slats 10 desirably, but not necessarily, formed of hollow backed flooring, the assembled block having tongues 11 on two sides thereof and grooves 12 on the remaining two sides with the juncture of the tongues cut away at an angle as at 13 for convenience in assembly in a floor, all of which is common practice.

10 To hold the blocks in assembly, I provide a contractile spring. As shown the spring comprises either a coil spring as 14, as shown in Figure 4, or a split ring as 14' shown in Figure 5. The coil spring 14 is the form of spring which I at present 15 prefer and when it is in position in the block, as shown in Figure 1, it will be straightened against its contractility into a circular form with its ends somewhat spaced apart. When the form of Figure 5, as shown at 14' is used, the contractility 20 depends upon the greater spacing between the ends, as shown in Figure 1, than the spacing of said ends before insertion in the block. The contractile spring either 14 or 14' is shown as placed 25 into a groove 15 which is formed in the slats 10 after they are placed together ready for reception of the spring, the groove thus formed in the assembled blocks preferably taking the form of a circle, as shown.

When the joints between the blocks are formed 30 as shown in Figure 2 with a relief 16 at the back of the block, the groove 15 is preferably formed with what might be called a "draft" as indicated at 17; that is to say, the groove considered as a whole at the open side thereof is not a frustoconical surface for substantially one-half the depth of the groove. This form of groove has two objects, first, it assists in the insertion of the spring, and second, it places the contractile action 35 of the spring above the central transverse plane of the block, so that the contractility of the spring acts as near as possible to the upper surface of the block where the upper edges of the slats are in contact to form a close joint.

However, when the blocks are formed with 40 square edges, as shown in Figure 3, that is, without the relief at the bottom of the joints, it is desirable to make the groove 17' perpendicular to the plane of the blocks in both of its sides.

The assembled block of the invention is found 45 to have considerable flexibility and if bent out of its normal plane, it will when released return to said plane. Moreover, if the slats of the block become separated, as by swelling and subsequent drying, the blocks, particularly when subject to 50

the action of traffic, will tend to return to a tight position by action of the contractile spring.

The return of the slats to plane after flexure is due not only to the rigidity of the spring which must be bent out of its normal plane with edge-wise flexure thereof when the block is warped, but such action also creates a strain against the contractility of the spring, since any two points in the groove at a joint between the slats are separated by such warping, thereby pulling the spring against its contractility and thus enlarging the circle of the groove. Such pulling causes the spring to bind against the inner surface of the groove.

15 As shown the spring is inserted into the groove so that the edge comes substantially flush with the bottom surfaces of the hollow backs in the block and therefore the spring considered as a spline will not interfere with the continuous nature of said hollow back grooves. When the blocks are laid in mastic in accordance with the common practice, the flow of mastic in the grooves will therefore not be interfered with.

20 Minor changes may be made in the physical embodiments of the invention within the scope of the appended claims without departing from the spirit thereof.

I claim:

30 1. A block of the class described comprising, in combination: a plurality greater than two of assembled slats; said assembly having a groove in one of its surfaces extending in the outer slats at an angle other than ninety degrees to the points between said slats; and a resilient spline 35 lying in said groove under tension tending to draw said slats together.

40 2. A block of the class described comprising, in combination: a plurality greater than two of assembled slats; said assembly having a groove in its lower surface comprising an arc of a continuous curve cutting across each joint between said slats; a resilient spline lying in said groove under tension tending to draw said slats toward each other.

45 3. A block of the class described comprising, in combination: a plurality greater than two of assembled slats having an annular groove in the

bottom surface of the assembly, cutting across each of the joints thereof; a resilient divided spline lying in tension in and substantially coextensive with said groove acting to urge said slats toward each other.

5 4. A block of the class described comprising, in combination: a plurality greater than two of assembled slats, the joints between said slats formed to provide relief at the lower surface of the assembly; an annular groove in the lower surface of said assembly, cutting across each of said joints and penetrating beyond the plane midway between the lower and upper surfaces of the assembly; the inner surface of said groove lying in a frusto-conical surface for at least a portion of its depth; a resilient spline lying in tension in said groove and exerting compressive stress above said plane to tend to keep the joints of said assembly closed at the upper surface thereof.

10 5. A block of the class described comprising, in combination: a plurality greater than two of assembled slats having an annular groove in the lower surface of the assembly cutting twice across each of the joints thereof; and a divided, resilient ring spline expanded against its resilience lying 15 in and substantially coextensive with said groove.

20 6. A block of the class described comprising, in combination: a plurality greater than two of assembled slats having an annular groove in the lower face of the assembly cutting twice across each of the joints thereof; and a resilient spline 30 initially of spiral form expanded to annular form and embedded in said groove, acting to press said slats toward each other and to resist warping of the assembled block.

35 7. A floor block comprising, in combination: a plurality greater than two of slats assembled in edge-wise engagement and having an annular groove formed in a surface of the assembly cutting twice across each joint between slats thereof; and a resilient divided spline lying in tension in and substantially coextensive with said groove; an exposed edge of said spline standing substantially flush with portions at least of the surface of the assembly in which said groove is formed. 40 45
